(57) **CLAIM**

The ornamental design for a percussive massager device connecting rod, as shown and described.

DESCRIPTION

FIG. 1 is a top view of the percussive massage device connecting rod;

FIG. 2 is a bottom view of the percussive massage device connecting rod of FIG. 1;

FIG. 3 is a front view of the percussive massage device connecting rod of FIG. 1;

FIG. 4 is a left view of the percussive massage device connecting rod of FIG. 1;

FIG. 5 is a right view of the percussive massage device connecting rod of FIG. 1; and,

FIG. 6 is an isometric view of the percussive massage device connecting rod of FIG. 1.

The broken lines in the drawings depict portions of the percussive massager device connecting rod that form no part of the claimed design.
